APPARATUS FOR MAKING CIRCULAR
BUSHINGS

John C. Lemming, Dayton, Ohio, assignor, by
mesne assignments, to General Motors Cor-
poration, Detroit, Mich., a corporation of Dela-
ware

Application November 25, 1931, Serial No. 577,246

5 Claims. (Cl. 153—49)

This invention relates to an apparatus for forming circular bushings or circular forms from flat metal stock and has particular reference to forming circular bearing bushings from flat strip bronze stock.

An object of the invention is to provide a simple and efficient apparatus for producing circular bushings having uniformly exact finished dimensions and which will have uniformly smooth and efficient interior bearing surfaces.

A feature of this invention is the reduction in diameter of the bushing in the final forming operation, whereby any tendency for the formed bushing to spring open slightly at the butt joint is avoided, and whereby such cold working of the metal improves the bearing qualities of the interior surface of the bushing.

Further objects and advantages of the present invention will be apparent from the following description, reference being had to the accompanying drawings, wherein a preferred embodiment of one form of the present invention is clearly shown.

In the drawings:

Fig. 1 shows a flat blank of strip bronze or other metal from which the bushing is to be formed.

Fig. 2 shows the flat strip being sheared off and bent into U-form by a reciprocating die.

Fig. 3 shows the U-form in position between two exterior half-dies and an interior floating arbor, just prior to the descent of the upper half-die.

Fig. 4 shows what happens during the first portion of the down stroke of the upper half-die. Here the bottom ends of the U-form have been bent inwardly under the floating arbor and caused said arbor to be raised somewhat to permit the ends of the U-form to come together easily.

Fig. 5 shows the completion of the down stroke of the upper half-die shown in Figs. 3 and 4. Here the U-form has been buckled out into approximately circular form by the dies and the central floating arbor has been forced to its down position and aids in causing the bushing to buckle out into substantially circular form though this circular form is not exact.

Fig. 6 shows another station where the bushing is being reformed to a more exact circular form and to slightly smaller inside and outside diameters which are its final dimensions. The dotted lines indicate the original size before reforming but the reduction in diameter is exaggerated to enable it to be shown. Here the metal of the bushing walls is flowed slightly under the high pressure of the exterior half-dies to form the bushing to exact dimensions and give the metal a permanent set.

Fig. 7 is a section on line 7—7 of Fig. 6 and

Fig. 5 and shows the successive forming operations of those two figures.

Fig. 8 is a section on line 8—8 of Fig. 6 and Fig. 5.

Similar reference characters refer to similar parts throughout the several views.

The drawings and following description refer to a method of making bearing bushings according to this invention.

The flat metal blank 10 is preferably sheared off from the end of a continuous strip 9 of flat stock of bronze or other suitable bearing metal by the edge 8 of the reciprocating die 12. If desired, oil grooves, holes and/or trade-marks may be stamped in the blank 10 by suitable dies 15 prior to the stroke of the die 12 which shears off blank 10. The blank 10 is then bent into the U-form 11 by the continued down-stroke of the reciprocating die 12 over the stationary central die 13. 14 is a stationary stripper bar which 20 aids in guiding the flat blank 10 into proper position between dies 12 and 13, and prevents the next following up-stroke of die 12 from dragging the U-form 11 up with it, all as will be clearly understood from viewing Fig. 2.

The U-form 11 next is passed endwise from its position on die 13 to the position shown in Fig. 3 where its lower ends 15 rest by gravity upon the curved surface 16 of the stationary lower half-die 20, the upper half-die 21 being 30 at that time at a higher position than as shown in Fig. 3 to provide proper clearance between it and the top of U-form 11. An interior floating arbor 22 is suitably supported in the position shown in Fig. 3 by a projecting end shank 19 (see Figs. 7 and 8) so that it may be easily moved vertically upward a small distance by the ends 15 of the U-form 11 as they are forced together as shown in Fig. 4. Floating arbor 22 has cylindrical surfaces 23, 24 and flat sides to enable it to properly 40 clear the sides of U-form 11 which at this time are much closer together than the full inside diameter of the bushing to be formed. Now when the upper half-die 21 descends it compresses the U-form 11 between dies 21 and 20 and causes 45 the lower ends 15 of the U-form to first cam inwardly on the semi-cylindrical surface 16 of die 20 until they pass under the freely floating arbor 22 and raise it upwardly by buckling at the points 25, all as clearly shown in Fig. 4.

From this point, further down movement of the upper half-die 21 rounds out the U-form 11 into the nearly circular form 30 as shown in Fig. 5. During this forming, the cylindrical surfaces 23 and 24 of arbor 22 aid materially in rounding out the top and bottom portions of the U-form 11 and this causes the flat sides of the U-form to always and uniformly buckle outwardly rather than inwardly even though said flat sides are spaced some distance from the interior arbor 22. An- 50 55 60 65 70 75 80 85 90 95

other very important function of the floating arbor 22 is to prevent the formation of a raised internal bead in the formed bushing 30 where the two ends 15 of the U-form 11 abut at high pressure when die 21 descends as described above. The diameter of the circular surfaces of arbor 22 is preferably several thousandths of an inch less than the inside diameter of bushing 30, formed as above described, to permit said formed bushing 10 30 to be easily slipped endwise from arbor 22 after the upper half-die 21 moves up again on its up-stroke. Since arbor 22 is floating, that is, it is not held in fixed position but may be moved upward freely for a short distance, the pressure of bushing 30 upon the lower half-die 20 is immediately released when die 21 starts on its up-stroke and hence this feature also permits easy endwise movement of bushing 30 from arbor 22.

For the final forming operation shown in Fig. 20 6 the bushing 30 is slipped endwise from the flattened arbor 22 onto the slightly smaller but full cylindrical arbor 42. This cylindrical arbor 42 is mounted upon a bolt 43 screwed into the end of floating arbor 22 and hence arbor 42 is 25 also floating (see Figs. 7 and 8). Preferably there is a small clearance 44 between the central aperture in arbor 42 and bolt 43 so that arbor 42 can move slightly relative to arbor 22, in order that the forming operation of Fig. 6 will be substantially independent of that of Fig. 5 even though the exterior half-dies 40 and 41 are formed integral with the half-dies 20 and 21 as clearly shown in Figs. 7 and 8. During this final forming operation of Fig. 6 all small bumps or 30 irregularities in bushing 30' are smoothed out and the walls of said bushing are compressed under high pressure between the half-dies 40, 41 and the central arbor 42 to such an extent that the metal thereof is flowed slightly to cause it to 35 permanently set in its formed exact dimensions. The cold working given the metal by the described reduction in diameter of the bushing at the station shown in Fig. 6 also improves the bearing qualities of bronze metal. At the next 40 up-stroke of upper half-die 41 the finally formed bushing 30' is slipped endwise from the end of arbor 42 by the movement to the left (as seen in Figs. 7 and 8) of the succeeding bushing 30 as it is moved to its position on arbor 42. Since 45 arbor 42 is slightly smaller in diameter than the cylindrical portion of arbor 22, bushing 30 slides easily to its position upon arbor 42. This movement to the left (as seen in Figs. 7 and 8) of both bushings 30 and 31 is done by automatic means 50 not shown since it forms no essential part of this invention.

It is to be understood that the operations described above preferably are continuous, that is, the U-form 11 is made at one station, the initial forming of bushing 30 is done at a second station, and the final forming of bushing 30' is done at a third station, all at one down stroke of the punch press carrying the dies corresponding to these three stations.

65 The bushings coming from the third station, that is, from arbor 42 may later have their ends cut smooth or chamfered in a suitable trimming machine if it is so desired, but otherwise these bushings are ready to be mounted as bearings 70 in the machine in which they are to be used.

While the form of embodiment of the present invention as herein disclosed, constitutes a pre-

ferred form, it is to be understood that other forms might be adopted, all coming within the scope of the claims which follow.

What is claimed is as follows:

1. Apparatus for making a circular bushing from a U-form metal blank comprising: two relatively reciprocating dies having coacting forming cavities which engage and compress said U-form blank therebetween and force same to buckle outwardly into circular form, and a flattened floating arbor positioned between said coacting cavities and having such cross section dimensions that said U-form blank may be passed thereabout prior to its being formed into circular shape, said floating arbor having surfaces which engage portions of the inside surface of the bushing as said dies form it into circular shape and thereby aid the circular forming therefor. 5 10 15

2. Apparatus for making a circular bushing from a U-form metal blank comprising: two relatively reciprocating dies having coacting forming cavities which engage and compress said U-form blank therebetween and force same to buckle outwardly into circular form, and a flattened floating arbor located within said die cavities when in closed position and having parti-cylindrical surfaces which engage the inside surface of the bushing while it is being formed into circular shape. 20 25

3. Apparatus for making a circular bushing from a U-form metal blank comprising: two relatively reciprocating dies having coacting forming cavities which receive and compress said U-form blank therebetween and bend same into circular form, and a flattened central arbor having diametrically opposed parti-cylindrical surfaces 30 35 which engage portions of the inside surface of the bushing being formed, said arbor having a sectional width less than its dimension across said parti-cylindrical surfaces whereby it may lie freely within said U-form blank prior to its bending into circular shape. 40

4. In an apparatus for making a circular bushing from a U-form metal blank, in combination, two relatively reciprocating dies having coacting substantially semi-cylindrical forming cavities 45 which engage and compress said U-form blank therebetween and force same to buckle outwardly into substantially cylindrical form, and a floating arbor positioned between said coacting dies and having a width materially less than the 50 inside diameter of the bushing to be formed so that said U-form blank may pass thereabout prior to its being buckled outwardly by said coacting dies.

5. In an apparatus for making a circular bushing from a U-form metal blank, in combination, two relatively reciprocating dies having coacting substantially semi-cylindrical forming cavities which engage and compress said U-form blank therebetween and force same to buckle outwardly 60 into substantially cylindrical form, and a floating arbor located between said coacting dies and movable relative to both of said dies to permit the opposed ends of said U-form blank to pass there-around while being bent into circular shape, said arbor having a width materially less than the 65 inside diameter of the bushing to be formed and having opposed parti-cylindrical surfaces which engage opposed inside surfaces of said bushing and aid in forming the same. 70
